UNITED STATES PATENT OFFICE.

NORTON A. NEWDICK, OF COLUMBUS, OHIO, ASSIGNOR TO THE COLODER COMPANY,
OF COLUMBUS, OHIO, A CORPORATION OF DELAWARE.

LOADING MACHINE.

Application filed December, 11, 1922. Serial No. 606,240.

This invention relates to improvements in loading machines and is especially directed to loading machines of the type employed in underground mines for the purpose of transferring mechanically loose, blasted down materials lying in bulk upon the floor of a mine into suitable cars or other carriers for transportation out of the mine or to other suitable points of discharge.

In accordance with the invention there is provided a loading machine which consists of a gathering conveyor, comprising an elongated inclined frame which has its rear or elevated end pivotally mounted about a compound pivotal support which enables the conveyor to swing bodily in both horizontal and vertical planes, with the forward or lower end thereof in engagement with the ground or floor, the said conveyor being formed to include an endless transmission belt arranged to pass around sprockets provided at the opposite ends of the frame and adapted for travel through substantially parallel guides, which are so disposed that the going and return runs of the belt will be situated in corresponding planes, the said belt being provided with a plurality of spaced laterally projecting conveying arms or flights, which upon movement of the belt and the swinging of the conveyor frame, will be brought into engagement with the materials to be loaded, carrying such materials through the conveyor in the line of draft of the machine, and finally depositing the same into suitable cars or carriers placed to the rear of the machine.

Among the objects of the invention are, first: To provide an improved mechanism upon the frame of the gathering conveyor by means of which the said conveyor is swung horizontally about its vertical pivotal support, and wherein the operation of said mechanism is effected by the source of power employed to drive the reversible transmission belt of the conveyor, and second, in the provision of an improved truck structure situated at the forward end of the gathering conveyor frame and mounted to assume active or inactive positions by means of which the machine may be readily transported over the track-way of a mine when being moved from place to place, when the said truck plate 4.

structure assumes its active position, with the front end of the gathering conveyor frame elevated from the floor and arranged in an elevated position removed from engagement with track obstructions, and wherein when the said truck structure occupies an inactive position, the front end of the gathering conveyor frame will be lowered for engagement with the ground and the truck structure itself maintained in a location free from hindering the sweep movements of the frame.

For a further understanding of the invention, reference is to be had to the following description and to the accompanying drawings, in which:—

Figure 1 is a side elevation of a loading machine constructed in accordance with the features of the present invention.

Figure 2 is a vertical sectional view taken through the gathering conveyor of the machine.

Figure 3 is a top plan view of said gathering conveyor.

Figure 4 is a vertical transverse sectional view taken on the plane indicated by the line 4—4 of Figure 3.

Figure 5 is a vertical section on the line 5—5 of Figure 4.

Figure 6 is a detailed vertical sectional view disclosing the drive mechanism between the head sprocket of the conveyor belt and the side swinging mechanism.

Figure 7 is a top plan view of the structure disclosed in Figure 6.

Referring more particularly to the details of the invention, the numeral 1 designates a loading machine comprising the present invention in its entirety. This machine is preferably of the type described in my co-pending application, Serial No. 439,092, filed January 22, 1921, and includes a portable base 2, in the form of a wheeled truck, arranged for travel over a trackway 3. Mounted upon the truck 2 for swinging movement in a horizontal plane about a vertical pivot disposed at the front end of the truck, is a bed plate 4, carrying at its front end a pair of bearings 5, which support for swinging movement in a vertical plane an oscillatory journal 6, through which passes a drive shaft 8, suitably driven from a motor 9 mounted upon the bed plate 4.

At its upper end the journal 6 pivotally supports the rear elevated end of the elongated inclined frame 10 of a gathering conveyor 11. The frame 10 is preferably constructed from suitably reinforced and braced structural sheet metal and is formed to include an elongated inclined body 13, which terminates forwardly in a substantially flat or depressed nose extremity 14, arranged for engagement, when the machine is in operation, with the floor of a mine or other surface upon which material is deposited for loading purposes.

The rear end of the body 13 terminates in the elevated horizontally disposed rear extremity 15, which rests upon the upper end of the journal 6 and is supported by the latter, so that the frame may swing bodily in a horizontal plane, or may vibrate vertically in unison with the journal 6. By this construction the conveyor is of such length as to sweep across the width, for example, of a mine room, to gather materials loosely deposited upon and across the floor 25 of said room, and to swing or move vertically to respond to unevenness in the floor surface upon which the nose extremity 14 rests.

The conveyor 11 includes centrally disposed laterally extending guides 16, mounted upon the bottom 17 of the frame 10 and disposed between the elevated sides 18 of said frame. These guides are adapted to receive the going and return runs of an endless transmission belt 19, which belt is arranged to pass around head and foot sprockets 20 and 21 respectively, situated at the opposite ends of the guides 16 and the frame 10. The head sprocket 20, in this instance, is mounted upon the upper end of the drive shaft 8 to rotate therewith, and consequently upon the operation of the motor 9, which is of a reversible type, motion may be imparted to the belt 19. The foot sprocket 21 is carried in a longitudinally adjustable clevis casting 22, by means of which the belt is maintained at a desired degree of tension.

Extending laterally from the belt is a plurality of spaced conveying arms or flights 23, which project laterally from guides 16 and are adapted for travel through material conveying ways 24 provided longitudinally in the frame 10, and situated between the guides 16 and the frame sides 18. It will be seen that in operation the movable flights 23 will pass around the foot sprocket 21 and brought into engagement with the materials deposited on the floor during the passage of aid flights through an arcuate course of travel. The flights are thus enabled to advance the materials gathered through the alternately available ways 24, and move the same through the conveyor 11 in the line of draft of the machine. The flights 23 pro-

ject beyond the rear extremity 15 of the frame when passing around the head sprocket 20, and thus the materials engaged with said flights are discharged at this point from the gathering conveyor and deposited within a hopper 25, out of which leads a delivery conveyor 26. The delivery conveyor is mounted upon the bed plate 4 to swing in unison with said bed plate, and is driven by the motor 9, the said delivery conveyor including an elevated overhanging rear end 27, arranged to project rearwardly of the truck 2 and to be arranged over a mine car not shown, into which materials handled by the machine are discharged and removed from the mine.

To effect horizontal swinging movement of the gathering conveyor 11, I provide upon the forward part of the frame 10 a pocketed sheave wheel 29, disposed for rotation in a substantially vertical plane, and having trained thereabout the intermediate portion of an ordinary anchor chain 30. The chain 20 has its links proportioned so as to be received within the pockets of the wheel 29, and is passed through hawse guides 31 carried in connection with the frame 10, so that the outer ends of said chain may be connected with a laterally disposed anchorage. By this construction it will be seen that upon rotation of the wheel 29 in a predetermined direction, the gathering conveyor will be swung horizontally and gradually in the direction of the lateral anchorage, enabling the flights to pass around the foot sprocket 21 to be maintained in engagement with the materials to be loaded.

In order to minimize the weight of the gathering conveyor so as to facilitate the handling of the latter, I provide an improved drive mechanism for the sheave wheel 29. This mechanism consists in providing the shaft 8 above the sprocket 20 with a miter gear 32, with which engages a similar gear 33 carried upon a tubular shaft 34, arranged for rotation within bearings 35 mounted upon the upper part of the frame 10. The outer end of the shaft 34 is provided with a jaw clutch member 36, arranged for engagement with a similar member 37, which is slidably keyed upon a shaft 38. This shaft has one of its ends journaled in the tubular shaft 34, and its other end in bearings. The member 37 is annularly grooved as at 39 for the reception of the fork 40 of a throw lever 41, which latter is pivoted as at 42 and is actuated by a manually controlled shaft 43, so that the slide clutch member 37 may be shifted longitudinally upon the shaft 38 into or out of engagement with the clutch member 36, thereby enabling the rotation of the shaft 38 to be governed at the will of the operator.

The forward end of the shaft 38 is pro-

vided with a bevel gear 44, meshing with a similar gear 45, carried upon a short transversely extending shaft 46, which is journaled in connection with the bearing 35. 5 The shaft 46 is provided with a sprocket 47, around which is trained an endless chain 48. The chain 48 extends longitudinally of the frame 10 and the forward part thereof is trained over a sprocket 49 carried upon a 10 short transversely extending shaft 50. This shaft also includes a bevel gear 51, arranged to mesh with a similar gear 52, mounted upon the shaft 53 upon which the sheave wheel 29 is mounted. It will be seen by this 15 construction the sheave wheel 29 may be rotated by the source of power employed for driving the belt 19, and a construction is hereby produced which eliminates the employment of a separate motor for driving 20 said sheave wheel, and the complicated and expensive worm gearing heretofore employed in transmitting the power of such a motor to the sheave wheel. Furthermore, not only is the construction simplified mechanically, 25 but the weight thereof is maintained at a minimum, so that the handling of the gathering conveyor may be more conveniently effected and less difficulty encountered in the 30 horizontal shifting of said conveyor and any vertical raising thereof.

To maintain the chain 30 taut while the forward end of the frame is being fed against the work, the member 37 is formed with small clutch teeth 54 at one end thereof, or the end opposite to the member 36. The teeth 54 are disposed to mesh with co-operating teeth 55 provided on the bearings 35, so that when the shaft 38 is disconnected from the shaft 34, the drive mechanism for imparting movement to the sheave wheel 29 will be automatically locked. This construction prevents undue turning on the part of the sheave wheel 29, and overcomes the reaction at the forward end of the machine which tends to shift the frame horizontally away from the work.

By reducing or minimizing the weight of the gathering conveyor, I am enabled to employ a lighter form of pony truck at the forward end of the gathering conveyor than disclosed in my aforesaid application. In previous constructions the weight of the gathering conveyor at the front end has compelled the use of a four wheeled pony truck, upon which the front end of the gathering conveyor is loaded when the machine is to be transported about the mine. In prior constructions this pony truck has been exceedingly awkward, heavy and cumbersome to handle, and has been detachably connected with the gathering conveyor, so that when the gathering conveyor is engaged in loading operations the pony truck 60 can be removed from beneath the forward 65 end of the same and located so as to occupy an inactive position out of interference with the gathering movements of the conveyor. However, a considerable loss of time has resulted in the use of four wheeled pony trucks because of the time taken to properly 70 position such trucks and to lower the front end of the conveyor thereon immediately prior to transportation of the machine over the track-way. However, in the present invention I am enabled to employ a two 75 wheeled pony truck structure, designated generally by the numeral 56, which structure is carried permanently by the forward end of the gathering conveyor and is quickly movable from active to inactive 80 positions so as to eliminate loss of time in the adjustment and positioning of the structure. As shown in the drawings, I accomplish this end by providing the under part of the frame 10 immediately to the rear of 85 the nose extremity 14, with bearings 57, in which is rotatably mounted a transversely extending shaft 58, provided at the outer ends with relatively flat extremities 59. These extremities are provided with openings 60 arranged for the reception of substantially vertical pivoting studs 61 carried in connection and arising from castor frames 62, in which frames are formed circular bearing heads 63 and wheel yokes 64. The 90 ends of the yokes 64 carry transversely and horizontally extending axles 65, about which are rotatably mounted track engaging wheels 66. It will be observed that by this construction the wheels 66 will be enabled to 100 turn horizontally about the substantially vertical axes provided by the studs 61, journaled in the ends of the shaft 58, so that the wheels 66 will readily adapt themselves to the curvature of a mine track. Also, to 105 exercise a stabilizing influence upon the wheels 66 and to prevent undue turning thereof while passing over frogs or track crossings, I provide the yoke 64 with rearwardly extending crank arms 67 which are 110 united at their outer ends by means of a tie rod 68, the said rod 68 serving to link the wheels 66 together, and to enable one of said wheels to maintain the other in proper 115 gaged relation.

Arising from the outer squared portions of the shaft 58 is one or more crank arms 69, arranged adjacent to a fixed segment 70 carried in connection with the frame 10. The upper end of the crank arm 69 is provided with a pivoted pawl or dog 71, which are adapted for co-operation with notches 72 provided in said segment for the purpose of maintaining the pony truck structure generally in fixed positions of adjustment. 120 It will be seen upon reference to the figures of the drawings, that when the front end 125 of the gathering conveyor is resting upon the ground, and the machine is actively positioned for loading operations, the 130

wheels 66 of the pony truck are revolved about the axis of the shaft 58, so that said wheels will be positioned beneath the inclined portion 13 of said frame, and elevated to a sufficient extent to avoid interference with materials or other obstacles lying upon the floor of a mine, the pawl 71 serving to maintain the wheels 66 so elevated. When thus positioned the gathering conveyor may operate without interference of any nature from the pony truck structure. However, after the materials have been loaded and it is desired to move the machine over a track-way 3, from one place to another, the pawl 71 is released from engagement with the segment 70 so that the wheels 66 may drop by gravity into engagement with the mine floor, or in other words immediately in advance of the ends of the forward rails of the track-way 3, as shown in Figure 2, whereby upon rearward movement of the loading machine the front end of said gathering conveyor will be elevated bodily by swinging about the axles 65 of the wheels 66, the said conveyor being elevated to an extent in which the yokes 64 are arranged vertically, or in other words, the shaft 58 is positioned vertically over the axles 65. When this alignment of parts occurs the pawl 71 drops into the notch 72, locking the pony truck wheels in their active positions, so that upon further rearward movement of the machine, the wheels 66 are drawn up, upon the track-way 3, permitting the machine to be readily transported around a mine.

It will be observed from the foregoing that the present invention provides a gathering conveyor consisting of but a minimum of operating parts wherein mechanical complication has been eradicated. The pony truck is constantly carried by the front end of the gathering conveyor, and the construction thereof is such that the operation of loading the gathering conveyor on the rails may be carried out in an extremely simple and rapid manner, overcoming the delays involved in the use of separate four wheeled pony truck constructions. The

pawl 71 is so constructed as to be readily released by hand operations.

What is claimed is:—

1. In a loading machine, a gathering conveyor including an elongated inclined frame, a support for the upper end of said frame permitting the latter to oscillate vertically, a pony truck for raising and lowering the front end of said frame, comprising a horizontally and transversely extending shaft rotatably journaled beneath the forward part of said frame, castor bearings turnable about axes at the ends of said shaft and disposed perpendicularly to the axis of rotation of said shaft, wheels carried by said bearings, and means for maintaining said shaft in fixed positions of rotation.

2. In a loading machine, an elongated inclined vertical movable gathering conveyor, a pony truck for the front end of said conveyor comprising a horizontally and transversely extending shaft, rotatably carried beneath the forward part of said conveyor, wheels carried by the outer ends of said shaft and rotatable about axes disposed perpendicular to the axis of rotation of said shaft, and connecting means between said wheels for imparting uniform movement thereto.

3. In a loading machine, a gathering conveyor, comprising an elongated inclined frame, a pivotal support at the rear end of said frame permitting the latter to move vertically, a pony truck structure at the forward end of said frame for controlling its vertical movements, said structure consisting of a shaft arranged to extend horizontally and transversely of said gathering conveyor at the forward part of said frame, castor bearings carried by the ends of said shaft and rotatable about axes arranged at right angles to the axis of rotation of said shaft, wheels carried by said castors, and means for locking said shaft in given positions of rotation.

In testimony whereof, I have signed my name to this specification.

NORTON A. NEWDICK.
